UNITED STATES PATENT OFFICE

HERMAN S. MURRAY, OF WOODMERE, NEW YORK, ASSIGNOR TO WILLIAM WILLHEIM CO., INC., OF NEW YORK, N. Y.

DESIGN FOR A TEXTILE FABRIC OR SIMILAR ARTICLE

Application filed October 22, 1932. Serial No. 45,494. Term of patent 3½ years.

To all whom it may concern:

Be it known that I, HERMAN S. MURRAY, a citizen of the United States of America, residing at Woodmere, Long Island, New York, have invented a new, original, and ornamental Design for a Textile Fabric or Similar Article, of which the following is a specification, reference being had to the accompanying drawing, forming a part thereof.

The figure is a plan view of a textile fabric showing my new design, the units of which, as shown, are repeated indefinitely in all directions.

I claim:

The ornamental design for a textile fabric or similar article as shown and described.

In testimony whereof I have signed this specification.

HERMAN S. MURRAY.
